UNITED STATES PATENT OFFICE.

HERBERT J. LA JOIE, OF ORANGE, NEW JERSEY, ASSIGNOR TO THE AUTOPIANO COMPANY, A CORPORATION OF NEW YORK.

TRACKER-BAR ATTACHMENT.

1,258,123.

Specification of Letters Patent.

Patented Mar. 5, 1918.

Application filed May 9, 1916. Serial No. 96,420.

To all whom it may concern:

Be it known that I, HERBERT J. LA JOIE, a citizen of the United States, residing at Orange, in the county of Essex and State of New Jersey, have invented a new and useful Tracker-Bar Attachment, of which the following is a specification.

This invention relates to an improvement on the device shown in Patent No. 1,173,652, granted February 29, 1916, for an invention made by Thomas Danquard in an attachment for tracker bars. This attachment consists of a spring clip or clips arranged so that the same can be snapped into operative position to hold the edge or edges of a music sheet closely against a tracker bar. This application covers an improvement on said attachment, and comprises mechanism for automatically throwing said means into and out of operative position.

This mechanism preferably consists of a pneumatic or pneumatics operatively connected with the instrument, so that when the note sheet is being drawn over the tracker bar for playing, the clip or clips will be automatically moved to operative position, and so that when the instrument is not being played or when the note sheet is being drawn backward over the tracker bar for re-rolling, the clip or clips will automatically be moved out of operative position.

The invention further consists of details hereinafter particularized and claimed.

The invention is shown in the accompanying two sheets of drawings in which—

Figure 1 is a front diagrammatic elevation, showing the preferred form of my apparatus;

Fig. 2 is a plan view thereof;

Fig. 3 is a front elevation of a modified arrangement;

Fig. 4 is an enlarged view, showing the operative mechanism, and

Fig. 5 is a sectional elevation taken on the line 5—5 of Fig. 3.

Referring first to the arrangement shown in the first sheet of drawings, it will be seen that the same is shown as applied to the well-known "Autopiano," the details of which are shown, for example, in patent to Danquard No. 766,601, patented August 2, 1904, for a manually or mechanically operated piano. The mechanism shown comprises a tracker

bar T, having the usual apertures and a perforated note sheet N which is wound on a 55 music spool which is placed in position in the apparatus, the note sheet being drawn over the face of the tracker bar by the usual drawing or take-up roll. A pneumatic motor is arranged at the right of the tracker bar, 60 and can be connected through suitable gearing so that the take-up roll will be revolved to draw the note sheet forward over the tracker bar for playing, or so that the music spool will be revolved for drawing the note 65 sheet backward for rerolling. The wind chest is connected to the action by the usual valve box 52 and connection 51, and the motor is connected to the wind chest in the usual way. The usual reroll lever is arranged in the instrument, and is provided with connections to the gearing between the motor and the drawing roll and music spool, to the valve governing the connection between the wind chest and action, and also 75 to the motor governor. These parts are arranged in the usual way so that when the re-roll lever is in its left-hand position, as shown, the wind chest will be connected to the action, and the gearing will be connected 80 to the motor so that the drawing roll will be rotated to draw the perforated note sheet forward over the tracker bar. When the re-roll lever is thrown to the right the wind chest will be disconnected from the action, 85 the wind chest will be freely connected with the motor, and the gearing will be so adjusted that the motor will rotate the music spool to draw the perforated note sheet backward over the tracker bar for rewinding. 90 These parts are of the usual and ordinary description, and require no further explanation.

A spring clip 10 has its ends pivoted in the tracker bar near the left-hand end thereof, as shown in Figs. 2 and 5, and is provided with an extending arm 11. This arm 11 is adjustably connected by a link 12 to the movable side of a pneumatic P, attached to the left-hand frame of the spool box. This 100 pneumatic P is connected by a tube p to the valve box 52. Another clip 13 has its ends pivoted to the tracker bar near its right-hand end, and is provided with an extending arm 14 which is adjustably connected by a 105 link 15 to the end of the link 12. A spring

16 is arranged normally to move the clips 10 and 13 to outward or inoperative position (as shown in Fig. 2).

When the instrument is being played, the 5 parts assume the position shown in Fig. 1, that is, as the exhaust is connected to the valve box 52, the pneumatic P will be collapsed to turn the clips 10 and 13 down to operative position, as shown in dotted lines 10 in Fig. 2, to engage the edges of the note sheet and hold the same closely to the tracker bar.

When the instrument is not being played, or when the perforated note sheet is being 15 rerolled, there is no exhaust in the valve box 52, and hence, the spring 16 will move the clips 10 and 13 to open or inoperative position, as shown in full lines in Fig. 2, the spring 16 also acting to expand the pneumatic P. Thus the clips 10 and 13 will automatically assume the proper positions depending upon what action is to take place.

In Fig. 3, a pneumatic P' is shown for 25 operating the left-hand clip 10, and a pneumatic P² for operating the right-hand clip 13, the pneumatics being connected to the clips by links 20 and 21 which have springs on the same tending normally to expand or open the pneumatics. The pneumatics P' 30 and P² are connected by tubes p' and p² to the valve box 52. By this arrangement the clips will be operated as previously described.

The clips 10 and arms 11 being made out 35 of spring wire, are yielding, so that the clips will engage the note sheet with a yielding tension.

By the arrangement shown, the clips will 40 be automatically moved to be into operative position when the instrument is being played, and will be automatically moved to inoperative position when the note sheet is being inserted, when the note sheet is being rewound, or when the instrument is not being played.

The details and arrangements herein 45 shown and described can be greatly varied by a skilled mechanic without departing from the scope of my invention as expressed 50 in the claims. Therefore I do not wish to be limited to details of construction, but what I do claim is—

1. The combination with mechanical devices for holding a note sheet against a 55 tracker bar, of mechanism effective to move said devices into operative position in front of said tracker bar and means effective to wholly remove said devices from the space in front of that portion of said bar normally 60 covered by the note sheet, thereby permitting unobstructed removal and insertion of the note sheet in a direction normal to the face of said bar.

2. The combination with mechanical de- 65 vices for holding a note sheet against a

tracker bar, of mechanism for throwing said devices into and out of operative position, a re-roll lever, and connections from said lever through which said mechanism is controlled.

70

3. The combination with mechanical devices for holding a note sheet against a tracker bar, of pneumatically controlled mechanism effective to move said devices into operative position in front of said 75 tracker bar when the note sheet is being drawn forward in playing, and means effective to wholly remove said devices from the space in front of that portion of said bar normally covered by the note sheet, when 80 the instrument is not being played, thereby permitting unobstructed removal and insertion of the note sheet in a direction normal to the face of said bar.

4. In a musical instrument, in combination, mechanical devices for holding a note sheet against a tracker bar, mechanism for throwing said devices into and out of operative position, and connections which render said mechanism effective to remove said devices from position in front of that portion of the tracker bar normally covered by the note sheet when the instrument is not being played.

5. In a musical instrument, in combination, mechanical devices for holding a note sheet against a tracker bar, mechanism for throwing said devices into and out of operative position, connections which render said mechanism effective to throw said means 95 into operative position when the note sheet is being drawn forward over the tracker bar for playing, and to remove said devices from position in front of said note sheet when the instrument is arranged to draw the note 100 sheet backward over the tracker bar for re-rolling.

6. In a musical instrument, the combination with clips at each end of the tracker bar for holding the note sheet against the same, connections between said clips whereby the same will move simultaneously into and out of operative position, and mechanism for throwing said clips into and out of operative position.

7. In a musical instrument, the combination with clips at each end of the tracker bar for holding the note sheet against the same, connections between said clips whereby the same will move simultaneously into and out of operative position, and pneumatic mechanism for throwing said clips into and out of operative position.

8. In a musical instrument, the combination with clips at each end of the tracker 125 bar for holding the note sheet against the same, connections between said clips whereby the same will move simultaneously into and out of operative position, and pneumatic mechanism, connected to the passage 130

extending from the wind chest to the action, for throwing said clips into and out of operative position.

9. In a musical instrument, in combination, means for holding a note sheet against a tracker bar, a pneumatic, connections from said pneumatic to said means through which said pneumatic is effective to press said means against said tracker bar, and resilient members acting through said connections to

remove said means from operative position when the pneumatic is released.

In testimony whereof I have hereunto set my hand, in the presence of two subscribing witnesses.

HERBERT J. LA JOIE.
